UNITED STATES PATENT OFFICE.

JAMES M. HYDE, OF SAPULPA, OKLAHOMA.

LATCH.

1,219,318.

Specification of Letters Patent. Patented Mar. 13, 1917.

Application filed September 23, 1916. Serial No. 121,792.

To all whom it may concern:

Be it known that I, JAMES M. HYDE, a citizen of the United States, residing at Sapulpa, in the county of Creek and State 5 of Oklahoma, have invented certain useful Improvements in Latches, of which the following is a specification, reference being had therein to the accompanying drawing.

The invention relates to locks and more 10 particularly to the class of mortise locks or knob latches for doors or the like.

The primary object of the invention is 15 the provision of a lock of this character wherein the construction thereof permits the mounting of the same within a door without weakening it and can be applied to one side thereof thereby eliminating the excessive cutting away of the door for accommodating the lock as it requires the boring of 20 only two holes for forming a seat for the casing of the lock.

Another object of the invention is the provision of a lock of this character wherein 25 the latch constitutes the locking bolt therefor and the same when thrown or in locking position will be held fast for the secure locking of a door or the like.

A further object of the invention is the provision of a lock of this character wherein 30 the construction thereof necessitates the assemblage of few parts which are arranged with respect to each other in a novel manner so as to render the lock compact, and said parts being readily accessible yet the 35 simplicity of the parts and the assemblage thereof eliminates any possibility of the lock becoming inoperative or ineffective for use.

A still further object of the invention is the provision of a lock of this character 40 which is extremely simple in construction, thoroughly reliable and efficient in operation, strong, durable, readily and easily applied to and removed from a door or the like, and inexpensive in manufacture and 45 installation.

With these and other objects in view the invention consists in the features of construction, combination of elements, and arrangement of parts as will be hereinafter 50 fully described, illustrated in the accompanying drawings, and pointed out in the claims hereunto appended.

In the accompanying drawings:

Figure 1 is a fragmentary side elevation 55 of a door frame and door showing the lock

constructed in accordance with the invention applied.

Fig. 2 is a fragmentary edge elevation of the door with the lock thereon.

Fig. 3 is a plan view of the lock casing. 60

Fig. 4 is a similar view with the cover plate removed.

Fig. 5 is a vertical longitudinal sectional view through the lock showing the latch bolt released. 65

Fig. 6 is a view similar to Fig. 5 showing the latch bolt locked.

Fig. 7 is a side elevation of the latch bolt.

Fig. 8 is a plan view thereof.

Similar reference characters indicate corresponding parts throughout the several views of the drawings. 70

Referring to the drawings in detail, A designates a portion of a door frame and B a portion of a swinging door which are of 75 the usual well-known construction and upon this swinging door is mounted the lock hereinafter fully described.

The lock comprises a casing 10 preferably in the shape of the numeral 8 and is fitted 80 at one side thereof with a removable cover plate 11 provided with a key hole or slot 12 and likewise the back of the casing if formed with a companion hole 13 for the reception of the end of the shank of the 85 key 14 when inserted within the hole or slot 12 for operating the lock mechanism herein-after fully described.

The lock casing 10 with the cover plate 11 which latter is detachably fastened there- 90 to through the medium of screws 15 are placed within a suitable mortise formed within the door B and cut correspondingly to the shape of the lock casing 10 for the reception thereof.

Mounted within the free edge of the door B in a suitable counterseat is a front guide plate 16 formed with a guide thimble 17 for the latch bolt 18 which is adapted to engage in a suitable keeper mounted in the 100 door frame A and this bolt is formed with a reduced threaded stem 19 which works through a suitable opening in the edge wall of the lock casing 10 and is detachably threaded in a lug 20 formed on the part 105 21 of the bolt and slidably fitted in a seat or guideway 22 formed in the bottom or rear wall of the lock casing 10. Passed transversely through the door, locking casing 10 and its cover 11 is a knob spindle 110

23 which is also passed through escutcheon plates 24 fastened to opposite faces of the door at the point of the lock casing 10 there-in and upon this spindle 23 at its ends there-
5 of are adjustably mounted door knobs 25 which permit the turning of the spindle for the operation of the latch bolt 18 in the manner presently described.

Carried on the spindle 23 is the hub 26
10 of a cam 27 which engages with an abut-
ment or lug 28 on the inner end of the part
21 so that said part and the latch bolt 18
detachably connected thereto can be oper-
15 ated for the unlatching of the door on oper-
ating either of the knobs 25 upon the ends
of the spindle 23 as will be apparent.

Arranged within the lock casing 10 in
the guide way 29 formed therein is a sliding
lock bolt 30 which is formed in one
20 edge with spaced notches 31 in either of
which is received a tooth 32 formed at one
edge of the guide way 29 for the lock bolt
30 so as to hold the latter in its thrown
25 position protruded into the run way or seat
22 for the part 21 or receded therefrom
so that in this manner the said part will
be held in its thrown position for holding
that latch bolt 18 in locking position or
30 said part 21 is free for retracting move-
ment within the lock casing to permit the
movement of the latch bolt 18 to unlocking
position.

The key 14 when inserted within the lock
casing 13 and turned will bring its bit 33
35 into engagement in a seat 34 formed in
the lock bolt 30 so that when the key is
being turned the bolt will be moved to
locking or unlocking position and also
moved in the direction to free it from the
40 tooth 32 prior to the sliding movement
thereof by the action of the key.

Suitably mounted within the lock casing
10 and working against the lug 20 of the
part 21 is a leaf spring 35 which automatic-
45 cally moves the tumbler in a direction to

throw the latch bolt 18 into locking posi-
tion. Also suitably mounted within the
lock casing 10 is a second leaf spring 36
which plays upon the sliding lock bolt 30
to positively move the same into position 50
for the engagement of the tooth 32 in either
of the notches 31 in said locking bolt so
that the latter will be held in its releasing
or locking positions.

From the foregoing it is thought that the 55
construction and manner of use of the
latch will be clearly understood and there-
fore a more extended explanation has been
omitted.

What is claimed is:

1. In a lock, a casing having a removable
cover plate and also provided with internal
run and guide ways at right angles to
each other, a part slideable within the runway
and having a lug, a locking bolt detach-
ably engaged in the lug, a sliding locking
bolt in the guideway and movable into and
out of the path of movement of said part, a
spindle operated cam for action upon said
part, a tooth formed in the guideway and 65
engageable with the locking bolt to hold
the same in adjusted position, and spring
means acting upon said part and bolt.

2. In a lock, a casing having a removable
cover plate and also provided with internal
run and guide ways at right angles to each
other, a part slideable within the runway,
a locking bolt detachably engaged in said
part, a sliding locking bolt in the guide-
way and movable into and out of the path 70
of movement of the part, a spindle operated
cam for action upon the part, a tooth formed
in the guideway and engageable
with the locking bolt to hold the same in
adjusted position, spring means acting upon 75
said part and bolt, and a guide plate hav-
ing a guide thimble for the latch bolt.

In testimony whereof I affix my signature.

JAMES M. HYDE.
